UNITED STATES PATENT OFFICE

CHRISTIAN STEENSTRUP, OF SCHENECTADY, NEW YORK, ASSIGNOR TO GENERAL ELECTRIC COMPANY, A CORPORATION OF NEW YORK

REFRIGERATING MACHINE

Application filed February 5, 1927. Serial No. 166,212.

My invention relates to refrigerating machines and particularly to electrically driven refrigerating machines adapted for domestic use. An object of my invention is to provide an improved refrigerating machine of this character having various features of construction which result in superior performance characteristics such as quiet running and freedom from stalling or overloading of the driving motor when running conditions are to be resumed after a shut down.

My invention will be better understood from the following description taken in connection with the accompanying drawing, and its scope will be pointed out in the appended claims.

Referring to the drawing, Fig. 1 is a vertical cross sectional view of a refrigerating machine involving my invention; Fig. 2 is a transverse cross sectional view of the same taken on the line 2—2 of Fig. 1; Figs. 3 and 4 are fragmentary cross sectional views of the mechanism drawn to a larger scale; Fig. 5 shows the exhaust valve and associated parts drawn to a still larger scale; Fig. 6 is a fragmentary cross sectional view showing the oil pump; and Fig. 7 is a perspective view of the main compressor and oil pump pistons.

In the drawing I have shown at 1 the upper portion of a refrigerator box, the top of which has an opening closed by the cover 2. Secured to the cover 2 and occupying a position within the box is the evaporator 3, the specific construction of which is disclosed and claimed in my copending application, Serial No. 148,266, filed November 13, 1926, assigned to the same assignee as the present application. Mounted on the top of the cover is a casing forming a gas tight chamber comprising the base 4, preferably a casting of relatively massive construction, and a bell 5 having relatively thin walls. The bell is provided at intervals with lugs 6 into which are threaded bolts 7 for firmly clamping the bell to the base, a suitable gasket being used to insure a gas tight joint. Resiliently supported within the casing and out of contact with the walls thereof is the operating mechanism comprising the refrigerant compressor 8, the

oil pump 9 and the driving motor 10, together with the driving connections, valves, etc. therebetween. The various parts of the operating mechanism are secured together by the frame 12 forming a separable unit. 55 For supporting this unit mechanism I provide the frame 12 with lugs 13 preferably three in number and equally spaced and between these lugs and the base 4 I provide coil springs 15. The opposite ends of these 60 springs are firmly secured respectively to the lugs 13 and to the base 4 by being threaded over grooved plugs 16 fastened to those members. The three springs thereby constitute a three point support for the operating mechanism, the strength of the springs being such that the mechanism is free to vibrate as a whole without transmitting those vibrations to the enclosing casing. 65

The casing, which as stated above, is gas 70 tight, is subjected to the pressure of the compressed refrigerant, the compressor exhausting into the casting and from the casing the compressed and heated gas escapes through pipe 20 into the condenser coil 21. 75 The other end of this coil connects with the float chamber 22 from which the condensed refrigerant is fed to the evaporator through inlet pipe 23. The casing is surrounded by a series of fins 25 by which the condenser coil 80 is supported and which being in good thermal connection with the coil and with the casing serve to increase the heat dissipation from both. Connection is made in part between the inlet of the compressor and the 85 outlet of the evaporator by the pipe 26 which after passing through the base 4 extends up into the bell and is formed into one or more turns 27 about the mechanism to enable it to yield readily to the vibrations of the mechanism. The turns 27 in this pipe are formed to slope upwardly from the evaporator so that should a slug of liquid be drawn up into it or run into it in the event that the machine is tipped sufficiently, the liquid will naturally drain back into the evaporator. Moreover, 90 since the coil is surrounded by the compressed gas, its temperature is such that small quantities of liquid refrigerant that may be drawn up will be vaporized before 100

reaching the compressor. For damping out vibrations that may travel along the turns 27, I tie the turns together as shown at 28 preferably by bands of silk as this material 5 does not affect and is not effected by the sulphur dioxide which I prefer to use as the refrigerant.

The pipe 26 through which the refrigerant gas is drawn from the evaporator terminates 10 in a valve support 30 (see Fig. 4) containing the valve 31 comprising a loosely fitting plunger body portion and a conical end portion which when the mechanism is at rest is 15 yieldingly withdrawn from its seat 32 by the coil spring 33. The upper portion of the support 30 is enclosed by a dome-shaped casing 34 forming therewith a surge chamber or reservoir 35. One side of the valve seat connects by passage 36 with pipe 26 and the 20 other side connects with the chamber 35 by two restricted passages 37. The valve support 30 is secured in a gas tight manner by screws 38 to the bottom plate 39 forming a part of the frame 12 and in which is the inlet 25 port 40 of the compressor. The valve support 30 has three openings 41, one only of which is shown, which connect with the passage 42 in plate 39 leading to port 40, a screen 43 being provided in passage 42 to prevent 30 any dirt or metal chips that may be in the system from entering the compressor. In the normal operation of the machine the valve 31 remains in the full open position illustrated, being so held by the spring 33 that 35 the gas taken by the compressor must pass the restricted openings 37. The compressor comprises the oscillating cylinder 45 mounted in trunnions 46 and a piston 47 journaled on the wrist pin 48. The drive shaft 49 which 40 is journaled in the frame 12 carries the wrist pin 48 at its lower end and is secured at its upper end to the rotor of the driving motor 10. For various obvious reasons it is desirable 45 to operate the mechanism at a relatively high speed but when so operated it has been found that the rapid intermittent movements of the gas drawn up from the evaporator is the cause of more or less noise and vibration, the evaporator itself being thereby set 50 into vibration. By means of the construction above described the transmission of impulse waves from the compressor to the intake pipe 26 and to the evaporator is greatly lessened, first by the mere provision of the 55 chamber 35 which constitutes an interposed reservoir where expansion and contraction of the gas may take place and second, by the combined provision of the chamber 35 and the restricted openings 37 through which the gas 60 enters the chamber in substantially steady streams.

In ordinary use, domestic refrigerating machines of the motor driven type such as disclosed herein are adapted to operate intermittently, the running and quiet periods be-

ing governed by suitable automatic temperature responsive devices. To facilitate restarting the mechanism after each period of inactivity, means have been provided for unloading the compressor by admitting gas pressure to the rear of the piston so that the pressure on the two ends of the piston would be substantially balanced, this condition continuing until the driving motor has attained substantially its normal speed. In my co-pending application, Serial No. 109,960, filed May 18, 1926, and assigned to the same assignee as the present application, I have shown unloading means which responds to the pressure of the lubricating oil which is 70 pumped only when the compressor is in operation. As in the aforesaid application, the compressor cylinder 45 has the small oil pump bore 52 into which fits the piston 53 connecting at its outer end with the bearing head 54 on the compressor piston 47, suitable co-operating ports being provided in the cylinder and in the bottom plate 39 whereby when the compressor is in operation oil is pumped from the sump formed by the base 4 into the 75 passage 55 lubricating the lower trunnion and the piston 47 and thence to the chamber 56 above the upper trunnion. From chamber 56 oil is led by passage 57 to the shaft and 80 wrist pin bearings from which the escape of oil is restricted to provide a predetermined back pressure in the chamber 56. Plunger 60 fits loosely in the chamber 56 and carries the spring pressed valve stem 61 which when 85 the plunger is raised by the pressure of oil being pumped engages its seat formed in the cap 62. Opposite sides of the valve seat connect respectively with the small passage 63 in the cap and with the pipe 64 whereby when 90 the valve 61 is in its open position, compressed gas from the interior of the casing is admitted to pipe 64. This pipe leads to the under side of the plunger valve 31 which 95 valve is closed against the tension of spring 33 by the gas admitted to pipe 64. Thus it 100 will be seen that during the normal running of the machine the oil pressure holds valve 61 closed and valve 31 remains open but as soon as the machine comes to rest the loss in oil pressure allows plunger 60 to descend opening valve 51 to admit gas pressure to pipe 64 whence valve 31 is closed. The body portion 105 of the valve 31, as stated above, fits loosely in the valve support 30 so that when the valve is closed gas conveyed by pipe 64 may pass the body portion and through the passages 37, 41, 42 and port 40 reach the compressor cylinder, thus partially, if not entirely, equalizing the pressure on the opposite ends of the 110 cylinder. When the machine is restarted and is coming up to speed the motor is thus relieved of much of the load and by the time it 115 has reached normal speed the oil pressure will have closed valve 61, whence valve 31 120 opens and normal operation is resumed.

As the plunger 60 (see Fig. 3) descends, due to loss of oil pressure incident to stopping of the pump, the edge 66 closes the oil passage 57 and thereafter the leakage of oil past the plunger permits the further descent to the position illustrated. To insure the rapid and positive downward movement of the plunger I have provided it with the channel 67 which is spaced from the edge 66 a distance substantially equal to the diameter of the oil passage 57 and is connected therewith by a small hole 68. When the pump is restarted the amount of oil that can pass through this hole 68 is not sufficient to prevent pressure being built up beneath the plunger 60 to raise it and close valve 61.

Should a quantity of liquid refrigerant or lubricating oil be drawn up from the evaporator it will be prevented by means now to be described from immediately entering the compressor cylinder, where it might damage the compressor. It will be noted that the outlet passages 41 from chamber 35 (see Fig. 4) are carried up to a point somewhat above the bottom of the chamber so that a sump is formed in the bottom of the chamber below the intake ends of these passages in which the liquid may collect. The lower portion of the sump thus formed connects by the small passage 70 with one of the passages 41 to permit any liquid which may have collected therein to be drawn off gradually with the gas on its way to the compressor.

The compressor cylinder 45, as already stated above, exhausts into the casing which encloses the mechanism. The exhaust valve (see Figs. 3, 4 and 5) comprises the thin flat plate 72 which is adapted to seat against the end face of the cylinder 45. The plate is retained and guided in its movement by the muffler casing 73 which is shown as rectangular in shape and as secured to the cylinder by screws 74. The valve plate 72 is resiliently held against the cylinder by spring means comprising the thin ring 75 which is slightly and evenly corrugated so as to provide a series of staggered uniformly spaced points of contact on opposite sides respectively with the valve plate and with the casing. The exhaust gas having passed the valve into the muffler casing escapes therefrom through a number of small openings 76. At 77 I have shown an additional spring between the plate and casing which spring, under certain circumstances, may be found unnecessary.

What I claim as new and desire to secure by Letters Patent of the United States is:—

1. A refrigerating machine comprising a gas tight casing, operating mechanism therein comprising a compressor, means for resiliently mounting the mechanism in spaced relation with the walls of the casing, an evaporator, a pipe connection between the compressor and the evaporator forming a plu-

rality of turns about the mechanism, and means comprising a tie between the turns for damping vibrations thereof.

2. A refrigerating machine comprising an enclosing casing, a compressor yieldingly mounted therein and arranged to exhaust compressed refrigerant thereinto, an evaporator, an inlet pipe for the compressor having connection with the evaporator and having a yielding portion comprising a spiral surrounded by the compressed refrigerant, the turns of said spiral being arranged to drain toward said evaporator.

3. A refrigerating machine comprising an evaporator, a compressor of the type producing a rapid intermittent movement of material through its intake, said compressor discharging compressed refrigerant into a chamber, an evaporator, a condenser connected between said chamber and said evaporator, an inlet pipe having connection with the evaporator and having a yielding portion comprising a spiral surrounding the compressor, and means providing a connection between said pipe and said compressor, said means having formed therein a surge chamber for damping further progress of waves incident to said intermittent movement.

4. A refrigerating machine comprising an evaporator, a refrigerant compressor, a connection therebetween, a valve in the connection, means for normally retaining said valve in open position so that the refrigerant may pass therethrough during the operation of the compressor, and means independent of the pressure in said connection for causing said valve to close when the compressor comes to rest.

5. A refrigerating machine comprising an evaporator, a refrigerant compressor, a connection therebetween, a valve in said connection arranged to be closed by compressed refrigerant, resilient means for holding said valve in open position, and means independent of the pressure in said connection for admitting compressed refrigerant to close said valve whenever said compressor comes to rest.

6. A refrigerating machine comprising an evaporator, a refrigerant compressor, a connection therebetween including a surge chamber, a valve in said surge chamber, means for normally retaining said valve in open position so that the refrigerant may pass therethrough during the operation of the compressor, and means for utilizing the pressure of the refrigerant on the high pressure side of said compressor for closing said valve whenever said compressor comes to rest.

7. A refrigerating machine comprising an evaporator, a refrigerant compressor including means for producing an auxiliary fluid pressure, a connection between said compressor and said evaporator including a surge chamber, a valve in said surge chamber, means for normally retaining said valve in open

- position so that the refrigerant may pass therethrough during the operation of the compressor, and means including a second valve controlled by said auxiliary fluid pressure for utilizing the pressure of the refrigerant on the high pressure side of said compressor for closing said valve in said surge chamber whenever said compressor comes to rest.
- 10 8. A refrigerating machine comprising an evaporator, a refrigerant compressor having a lubricating pump, a connection between said compressor and said evaporator including a surge chamber, a valve in said surge chamber, means for normally retaining said valve in open position so that the refrigerant may pass therethrough during the operation of the compressor, and means including a second valve controlled by the pressure of said lubricating pump for utilizing the pressure of the refrigerant on the high pressure side of said compressor to close said valve in said surge chamber whenever said compressor comes to rest.
- 15 20 25 In witness whereof, I have hereto set my hand this 3d day of February, 1927.

CHRISTIAN STEENSTRUP.
